(57) **CLAIM**

The ornamental design for a tattoo machine grip, as shown and described.

DESCRIPTION

FIG. 1 is a perspective view of a tattoo machine grip.

FIG. 2 is a first side view of a tattoo machine grip.

FIG. 3 is a top view of a tattoo machine grip.

FIG. 4 is a bottom view of a tattoo machine grip; and,

FIG. 5 is a second side view of a tattoo machine grip.

The broken lines showing the remainder of the tattoo machine grip are directed to environment and are for illustrative purposes only; the broken lines form no part of the claimed design.
